UNITED STATES PATENT OFFICE

JOHN F. GLASER, OF CHICAGO, AND CLYDE M. GLASER, OF OAK PARK, ILLINOIS

ADVERTISING DEVICE

Application filed October 14, 1929. Serial No. 399,490.

This invention relates to a display device, and more particularly to a revolving sign in which the movement thereof causes a complete image or advertisement to be produced.

Formerly, signs of this type have consisted of a plate, which carries a complete symbol or advertisement on each face, said plate being rotated slowly in order that the symbol or advertisement on one face may be noted by an observer before the next symbol or advertisement on the other face is presented. Some of the prior art devices have included a plurality of movable slats in alignment, each slat having upon one face a portion of an advertisement and on the other face a portion of a different advertisement. Some form of operating mechanism is usually provided for causing one face of all the slats to be presented to an observer, thereby forming a complete symbol or advertisement; and then rotating the slat so that the other face of each slat is presented and another complete symbol or advertisement formed. Since all of these devices are moved at a relatively slow speed, it is evident that some sort of gearing, reversing means or other complicated mechanism must be used; the result being that the sign is complicated and expensive. Another objection to the prior art devices is that although the movement of the device will attract the attention of a casual observer, the movement is relatively slow, thereby making it necessary for an observer to wait for the presentation of a complete symbol or advertisement if the sign is in the process of changing from one advertisement to the other. It is evident that with the slow movement, there are certain positions in which the observer cannot read any advertisement.

It is, therefore, an object of this invention to provide a revolving sign of simple and inexpensive construction.

It is also an object of this invention to provide a device in which portions of indicia are alternately displayed in a manner such that visually a complete image is produced.

It is a further object of this invention to provide a novel advertising device to which the attention of a casual observer is drawn

by reason of the alternate displaying of partial indicia which visually form a complete image.

Other and further important objects of this invention will be apparent from the disclosures in the accompanying drawings and the following specification.

The invention (in a preferred form) is illustrated on the drawings and hereinafter more fully described.

On the drawings:

Figure 1 is an elevational view of a device embodying this invention.

Figure 2 is a sectional view of the device taken substantially on line II-II of Figure 1.

Figure 3 is an isometric view of a modified form of the device.

Figure 4 is a plan view of one of the faces of the revolving plate shown in Figure 3 and having a portion of a complete image thereon.

Figure 5 is a plan view of the other face of the revolving plate shown in Figure 3 having a complementary portion of the complete image thereon.

As shown on the drawings:

In the illustrated embodiment of this invention, there is shown in Figure 1 a container. The word "container" is here used in its generic sense, and it is not the intention to limit its use to any specific structure. In this instance, however, the container comprises an open box-like frame 1 which should have a relatively narrow depth. Side members 2 of a translucent material such as glass are held in position against the corners of the box-like frame by means of angle corner members 3, which are fastened in position in any well-known manner. End members 4, preferably constructed of metal, are held in position between the box-like frame and the angle corner members. The container is supported for rotation about its longitudinal axis; a short shaft 5 being secured to one of the end members and extending normally thereto and a hollow shaft 6 to the other end member and extending normally thereto. The shaft 5 extends through a bearing 7 supported upon a pedestal 8 which is connected

to a base plate 9 by means of holding down bolts 10. The outer end of this shaft may be directly connected to any well-known power means such as an electric motor or may be driven through a belt 11 and pulley 12 which is secured to the shaft by means of a pin 13. The inner end of the hollow shaft 6 has an electric socket 14 secured thereto for receiving a light bulb 15 which is thereby supported intermediate the translucent side members 2 of the container. Electrical connection is made to the socket by means of the conductors 15 and 16 which are carried within the hollow shaft 6 and are connected at their outer ends to the collector rings 17 and 18 respectively. These collector rings are supported and electrically separated by an insulating collar 19 which surrounds the outer end portion of the shaft and is connected thereto in any suitable manner. This shaft extends through a bearing 20 supported by a pedestal 21, which is secured to the base plate 9 by means of holding down bolts 22. Brushes 23 and 24 bear against the collector rings 17 and 18 and provide a continuous electrical connection to the socket. These brushes are supported upon a brush support stud 25 secured to the pedestal 21.

Each translucent side member of the box-like structure carries a portion of a complete image, which may be in the form of an advertisement, lettering, pictures or the like. For example, there is illustrated a complete image consisting of the letters "O H". It is to be observed that the right half 26 of the letter "O" and the left half 27 of the letter "H" are carried by one of the side members of the container, and that the complementary portions of these letters, comprising the left half 28 of the letter "O" and the right half 29 of the letter "H", are carried by the other side member of the container. It is now evident that, if the box-like container is rapidly rotated about its longitudinal axis, an observer will alternately see first one side member and then the other side member, each carrying a portion of the complete image. Since the change from one portion of the image to the other portion of the image is more rapid than can be followed by the eye, a complete image will, therefore, appear to the observer. The rotation of the box-like container will attract the attention of a casual observer.

Although in the preferred form of this invention, it is desirable to provide the box-like container with translucent sides, which are illuminated, the invention may be constructed in a modified form as shown in Figure 3. In this form, instead of using a box-like container, a plate 30 having portions of a complete image on its side faces, is trunnioned at its end, for rotation about its longitudinal axis. In the modified form, however, outside or general illumination is relied

upon rather than providing an illuminating means as in the preferred form of the invention. Although a pulley and belt are shown connected to one of the trunnions for rotating the plate, it is not the intent to limit the invention to this form of drive. It is contemplated that any form of power means may be used, such as a motor, which, in that case, could be connected directly to the trunnions. It is obvious that the invention may also be manually operated, if desired.

This invention provides a revolving sign of simple and inexpensive construction, which will attract the attention of a casual observer, the sign being provided with portions of indicia, which are alternately displayed in a manner such that visually a complete image is produced.

We are aware that numerous details of construction may be varied through a wide range without departing from the spirit of the invention, and we, therefore, do not purpose limiting the patent granted otherwise than necessitated by the prior art.

We claim as our invention:

An advertising device for successively exposing indicia, such as letters of the alphabet, to the eye of an observer, and to alternately expose parts of letters forming a group in oppositely directed and varying spaced apart position, said device comprising a rotatable hollow and translucent member, illuminating means in said member, and indicia on two sides of said member, such as letters of the alphabet, said indicia being so arranged on said member that, as it is revolved, complementary parts of letters forming a group appear oppositely and alternately in adjacent or normal spaced relation, and in spaced apart or abnormally spaced relation to each other, so that the parts merge to produce the illusion of completed letters as the member is rotated at high speed.

In testimony whereof, we have hereunto subscribed our names at Chicago, Cook County, Illinois.
